UNITED STATES PATENT OFFICE.

THOMAS E. McCARTHY, OF TWO HARBORS, MINNESOTA.

CAR COUPLING.

1,416,368.

Specification of Letters Patent. Patented May 16, 1922.

Application filed November 14, 1921. Serial No. 514,850.

To all whom it may concern:

Be it known that I, THOMAS E. McCARTHY, a citizen of the United States, residing at Two Harbors, in the county of St. Louis 5 and State of Minnesota, have invented certain new and useful Improvements in Car Couplings, of which the following is a specification, reference being had therein to the accompanying drawing.

10 This invention relates to car couplers and has special reference to means for indicating accidentally broken knuckle pins in draw bar heads.

The principal object of the invention is 15 to provide simple means whereby a broken knuckle pin will be instantly and prominently indicated so that a trainman will readily detect same and thus avoid many serious accidents now resulting from such

20 broken pins.

Other objects and advantages of the invention will appear in the further description thereof.

Referring to the accompanying drawing 25 forming part of this application in which like reference characters indicate like parts:

The figure is an elevation of a common draw bar head such as found in the Tower or Janey coupler.

30 The common draw bar head is provided with a vertically disposed knuckle pin 1 which pivotally supports the knuckle 2, the body portion of the head being indicated at 3.

35 These pins are usually held in position against dislodgement vertically by a common cotter pin indicated at 4, and, as is well known to those versed in the art of railroading, the pins 1 are frequently broken.

40 When such an accident happens the lower portion of the pin will drop out of the hole in which it had been originally housed. In this condition a car may proceed upon its journey with no one having knowledge of 45 the fact that the pin was broken and have frequently travelled with a pin thus broken some considerable distance, from forty to fifty miles depending upon individual circumstances, with the upper portion only of

50 the pin holding, until finally the coupling is broken or lets go, frequently resulting in serious accidents.

Had the trainmen known of the broken pin in the coupler they would doubtless have remedied same before an accident occurred 55 and in fact such instances are known to exist for there is already on the market a pin supporting device in the form of a finger formed integral with the lower portion of the body 3 of the head and which finger extends outwardly centrally of the hole in which the pin is located and which will prevent the falling out of the lower portion of a broken pin. However such a device is not considered adequate for the purpose, as if, 60 under such circumstances, a pin is broken the lower end will simply drop slightly until arrested by the finger where it would not be observed nor given attention, for it would not appear any different from a solid or 65 perfect pin.

In my present invention I attach to the head of the cotter 4 a short piece of chain 5, which, at the other end, is attached to a suitable eye-bolt 6, or other fastening as desired, in the lower half of the body portion 3 of the head. This chain is made sufficiently long to permit of preferably at least one-half of the pin to fall completely out of the hole and dangle as it were down from the 70 draw bar head as shown in dotted lines at 7. Thus being suspended from the head it becomes instantly discernible at a reasonable distance by any trainman and makes it possible for the defect to be corrected before an 75 accident occurs to the train.

It is to be understood that the chain and pin may be of various forms and the chain attached otherwise than as shown, but the broad conception of the invention is obvious 80 and clearly pointed out in the following claims.

1. The combination with a draw bar head having a vertically disposed knuckle pin therein and a cotter key through the lower end of the pin for retaining it in position, of flexible suspending means attached at one end to the key and at the other end to the draw bar head whereby the lower portion of a broken pin will drop from the head and 95 be suspended therefrom for the purpose described.

2. The combination with the knuckle pin of a draw bar head of the character de-

scribed, of means to prevent the upward movement of said pin while in position and to retain in suspension externally of the head the lower portion of said pin which 5 might be accidentally detached from the upper portion whereby to prominently indicate impending danger.

In testimony whereof I hereunto affix my signature in the presence of two witnesses.

THOMAS E. McCARTHY.

Witnesses:

S. C. BRONSON,
S. GEO. STEVENS.
